CLAIM

The ornamental design for a portable video system, as shown and described.

DESCRIPTION

FIG. 1 is a top, rear perspective view of a portable video system showing my new design;

FIG. 2 is a top, rear perspective view thereof, shown with a video camera mounted on the handle;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

FIG. 2

FIG. 3

FIG. 4

FIG. 5

FIG. 6

FIG. 7

FIG. 8
